UNITED STATES PATENT OFFICE.

CHARLES W. SURPLUS, OF CHICAGO, ILLINOIS.

REICING-PLATFORM.

SPECIFICATION forming part of Letters Patent No. 755,075, dated March 22, 1904.

Application filed September 26, 1903. Serial No. 174,838. (No model.)

To all whom it may concern:

Be it known that I, CHARLES W. SURPLUS, a citizen of the United States, residing at Chicago, in the county of Cook and State of Illinois, have invented a Reicing-Platform, of which the following is a specification.

My invention relates to the reicing of perishable goods, (meats and fish especially,) and the objects are, first, to save time; second, to save handling goods; third, to reice top and bottom of goods without removing goods from the original package. I attain these objects by the reicing-platform illustrated in the accompanying drawings.

Figure 1 is the top view of platform. Fig. 2 is the side view of platform. Fig. 3 is a vertical section of a portion of the platform in position. Fig. 4 is the isometric view of platform. Fig. 5 is the hinge with one end (No. 4) tapered and turned.

Similar letters refer to similar parts throughout the several views.

The size of the platform depends on the size of the box and the open space between the top of goods and cover of box.

A represents the upper part of platform.

B represents the lower part of platform.

Nos. 1, 2, and 3 are cross-sections to which A and B are fastened and are as long as A is wide and are placed equal distances from each other and from the ends of A.

The space between the top of A and the top of B should be one-half the open or ice space in box when goods are in box to be reiced.

A is a trifle smaller than the inside measurement of box, so as to allow an easy fit.

B is the same size as the outside measurement of box.

Nos. 1, 2, and 3 are as thick and wide as necessary, depending on height of platform.

In the accompanying drawings, Nos. 1, 2, and 3 are represented as two by fours and A and B one-inch boards.

Fig. 5 represents platform-hinge one-eighth inch thick and one and one-half inches wide, made of wrought-iron, the upper or free end marked. No. 4 tapers at end to one inch and turned one-half inch toward platform, running to a sharp edge. The lower part of hinge is fastened to under side of B at 1 and 3, as shown in Fig. 4. No. 4 has a hole near top for a nail, if required.

As to working, when the box to be reiced is opened at the top place the reicing-platform down over the top, A side in, and fasten the cleats or turned points (No. 4) into the side of the box, then turn the box over, (see Fig. 3,) remove the bottom of the box, and fill the open space with ice, renail the bottom, reverse the box, remove the platform, and fill the space with ice. We then have goods reiced top and bottom alike. Goods are not broken, handled, or removed from the original package.

What I claim as my invention, and desire to secure by Letters Patent, is—

A reicing device consisting of a platform adapted to fit within a receptacle to be reiced, means for limiting the inward movement of the said platform consisting of a second larger platform fitting over the opening in the said receptacle, spacing means for securing the platforms in a fixed relation, and means for securing the device to the receptacle, comprising hinges each having one member secured to the outer platform and the other member provided with an inturned end.

CHARLES W. SURPLUS.
